UNITED STATES PATENT OFFICE.

JAMES T. FENNELL, OF PHILADELPHIA, PENNSYLVANIA.

STEAM-SEPARATOR.

1,202,043.

Specification of Letters Patent. Patented Oct. 24, 1916.

Application filed September 21, 1915. Serial No. 51,754.

To all whom it may concern:

Be it known that I, JAMES T. FENNELL, a citizen of the United States, residing at Philadelphia, in the county of Philadelphia and State of Pennsylvania, have invented 5 certain new and useful Improvements in Steam-Separators, of which the following is a specification.

My invention relates to improvements in 10 steam separators, and more particularly to an inside steam separator located in the upper portion of the boiler shell and around the steam outlet, said separator operating to catch water of condensation on the inner 15 face of the boiler shell, and prevent the escape thereof with the steam.

A further object is to provide an improved 20 construction of separator which will present a smooth surface to the steam in its passage from all directions, and which is provided with an improved arrangement of drain spout removably secured to the separator and carrying the water to one side of the 25 boiler, whereby a maximum of head room is permitted in the boiler.

A further object is to provide an improved 30 construction of conical baffle which not only directs the steam into the outlet, but also operates to catch water of condensation and direct the same back into the boiler.

A further object is to provide an improved 35 construction of separator which can be readily assembled within the boiler, and which can be varied to suit any style of boiler in connection with any arrangement of outlet 40 pipe or coupling at the outlet for steam in the boiler.

With these and other objects in view, the 45 invention consists in certain novel features of construction and combinations and arrangements of parts as will be more fully hereinafter described and pointed out in the claims.

In the accompanying drawings: Figure 1 50 is a fragmentary view in cross section illustrating my improved separator in position in a boiler. Fig. 2 is an enlarged sectional view of the separator similar to Fig. 1 but a fragment of the spout being shown. Fig. 55 3 is a fragmentary view in section on the line 3—3 of Fig. 2. Fig. 4 is a view in elevation of the separator with the spout removed, and Fig. 5 is an end view of the spout.

1 represents a boiler shell, and 2 is a steam outlet pipe preferably having a screw-

threaded end 3 which is screwed through an opening 1^a in the boiler shell 1. This opening 1^a is reinforced by a ring 1^b, but of course such details of construction are immaterial, and may be varied at will.

4 represents my improved separator which comprises a ring having a tapering central opening 5, and having internal screw-threads 6 at its upper end to receive the 65 screw-threaded lower end of pipe 2.

The ring 4 is so shaped as to provide on its upper surface an annular gutter 7, the wall of this gutter in cross section curving in a slightly different degree from the curvature of the bottom of the separator, and the wall of the opening 5, so that said separator is thickest at its intermediate portion and gradually tapers to its outer edge. The gutter 7 is provided with an outlet recess 8, 70 which is located in the side of the separator, and has its lower portion in a plane above the bottom of the gutter, so that a small amount of water is always maintained in the gutter, which is desirable in structures 75 of this character. Around the lower portion of the outlet recess 8, an integral lip 9 is formed on the outer face of the separator, and tapers to a sharp outer edge 10.

11 represents my improved spout which is 80 provided at its upper end with two integral hooks 12, which are positioned over the edge of the separator while the intermediate portion of the spout at its end engages under the lip 10 as shown clearly in Figs. 2 and 3. 85

The hook portions 12 of the spout 11 are provided with openings 13 which register with openings 14 in the separator, and are adapted to receive bolts 15 to secure the parts together. When these bolts 15 are 90 removed, the spout can be disconnected from the separator by moving the spout from under the lip 10 and then lifting the hooks 12 from the edge of the separator.

It will be noted particularly by reference 100 to Fig. 2 that the spout 11 at its point of juncture with the separator conforms in shape to the shape of the lip 10 so as to provide a smooth and secure coupling of the two parts.

With my improved arrangement of removable spout, the parts can be readily assembled within the boiler structure, and by locating the spout so that it curves to one side of the boiler shell, I provide a maximum of head room within the boiler which is of course desirable.

Below the separator 4, I locate a conical baffle 16 which on its upper face conforms to a large extent to the curvature of the separator, so that an annular entrance is provided to the pipe 2 which allows the steam to enter from all directions, and which prevents a direct flow into the pipe without first contacting with metal surfaces.

The baffle 16 is connected to the separator 10 by bolts 17 having spacing sleeves 18 around the same, so that the parts are readily removable as occasion may require.

It will be noted that with my improved construction, I employ no pipes which are liable to become stopped up, and interfere with the perfect operation of the separator, and it will also be noted that my improved construction embodies three parts which can be readily separated within the boiler structure, and hence my invention not only performs its functions of separating the water from the steam, but also is so put together as to facilitate its removal or disconnection whenever desired, and at the same time allow a maximum of head room in the boiler as the drain spout curves to one side of the boiler and discharges the water adjacent the shell of the boiler.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A separator of the character described having an annular gutter and an outlet re-

cess, said separator having an integral lip around the outlet recess, and a removable drain spout secured to the separator and positioned under the lip, substantially as 45 described.

2. A separator of the character described having an annular gutter and an outlet recess, said separator having an integral lip around the outlet recess, a removable spout positioned under the lip and having hooks 50 at its ends located over the edge of the separator, substantially as described.

3. A separator of the character described having an annular gutter and an outlet recess, said separator having an integral lip around the outlet recess, a removable spout positioned under the lip and having hooks 55 at its end located over the edge of the separator, said separator and hooks having registering openings therein, and securing devices in said openings, substantially as described.

4. The combination with a boiler, of a separator located around the steam outlet of 65 the boiler and having an annular gutter and an outlet recess, said separator having an integral lip around the outlet recess, a removable spout positioned under the lip and having hooks at its end located over the 70 edge of the separator, said spout extending to one side of the boiler and discharging the water from the separator at a point adjacent the side wall of the boiler, substantially as described.

In testimony whereof I have signed my name to this specification in the presence of two subscribing witnesses.

JAMES T. FENNELL.
